UNITED STATES PATENT OFFICE.

JOHN ALLEN HEANY, OF NEW HAVEN, CONNECTICUT.

INCANDESCENT ELECTRIC LAMP.

Application filed November 27, 1918. Serial No. 264,320.

To all whom it may concern:

Be it known that I, JOHN ALLEN HEANY, a citizen of the United States, and a resident of New Haven, in the county of New Haven 5 and State of Connecticut, have invented a certain new and useful Improvement in Incandescent Electric Lamps, of which the following specification is a full, clear, and exact description of the invention, such as 10 will enable others skilled in the art to which it appertains to make and use the same.

In my improved incandescent electric lamp, I make use of a luminant, which consists of a base of highly refractory material 15 capable of becoming highly incandescent when sufficiently heated, with which is associated a heating element or resistor of a highly refractory metal wire which is so arranged with respect to the refractory base 20 that it supplies the heat necessary to cause the same to become incandescent. The luminant is supported in the usual glass container, which may either be evacuated or filled with a suitable inert gaseous medium. 25 The usual leading-in wires extend from the stem of the lamp into approximately the center of the container. Carried by the lower ends of the leading-in wires are short spud-wires which are shaped to engage with 30 the base. These wires are made of a metal such that in small diameters it is quite stiff and a poor conductor of heat. These wires are made use of because it is highly desirable that heat should not unnecessarily be conducted away from the base. If the base was carried by the usual lead wires instead of 35 these spud-wires, a large amount of heat would be conducted away, due to the fact that such wires are quite good conductors of 40 heat and would necessarily have to be fairly large in diameter to be stiff enough to hold the base in proper position. By using a metal such as molybdenum, having the properties above mentioned, the spud-wires can be 45 made so fine that the heat conducted away by the spud-wires is not enough to dissipate an unnecessary amount of heat. The resistor wires are also connected to the ends of the leading-in wires, forming a closed circuit 50 therethrough. To make the assembling of the lamp as practical as possible and to avoid unnecessary operations, the resistor and the spud-wires are connected to the

leading-in wires by the same connecting joint. This application is directed to the 55 connecting joint.

It is essential that the joint connecting the three wires be substantial and strong and at the same time be small and compact. The three wires are all of different diameters and 60 the largest of them—the lead wire—is quite small, the resistor wire being extremely fine. This means that the connecting joint must be of small size and consequently difficult to fabricate unless a simple sort of joint has 65 been devised.

The joint used by me consists of a sleeve by means of which the three wires—the extremely fine resistor wire, the slightly larger spud-wire, and the still larger lead wire—70 are all joined firmly together. The lead wire and the spud-wire each extend half way through the sleeve and meet at the midpoint. The resistor wire extends throughout the whole length of the sleeve. The sleeve 75 is larger at one end than at the other and is approximately elliptical in cross-section. The sleeve grips the two smaller wires along a transverse line at its smaller end and then tapers away from these wires somewhat to 80 conform to the size of the lead wire, which it grips fairly uniformly throughout.

I am aware that it is old in the art of incandescent electric lamps to use a sleeve to connect two wires of approximately the 85 same cross-section, but do not believe that a sleeve has ever been used in this art to join three wires all of different sizes. A sleeve was used quite early in the incandescent lamp art to join a filament to a platinum lead- 90 ing-in wire. In this case the two wires joined together were of about the same diameter. A sleeve constricted at its mid-point was slipped over the end of the filament and cement applied to hold the filament to the sleeve. The sleeve was then slipped over the exposed end of the platinum lead wire and crimped so as to insure 95 a good contact between the sleeve and the lead wire. The logical advance in the art 100 was to do away with using cement to fasten the filament to the sleeve and instead simply crinkle, crimp or otherwise compress or distort the sleeve both on the filament and the lead wire to form a tight joint.

One of the most recent applications of a

sleeve to connect two conductors in electrical appliances was designed for use more especially to attach "wires which, on account of their physical form or the nature of the materials of which they are composed, cannot readily be united by soldering, brazing or welding." This joint was intended for use more especially "in joining a rod or wire to a flexible conductor composed of a number of twisted strands of fine wire." This joint united two elements of the same size and is featured by the fact that the sleeve is compressed uniformly about the two elements, a feature present in the prior means of attaching the lead wire and the filament but which was apparently thought to be subservient to the crinkling feature.

None of these prior connecting means intimate in any way that they could be used to join three wires all of different sizes to make a firm union between them. They are all based on the idea of a uniform contact throughout between the wires and the sleeve and can only be used, as they are set forth in the prior art, to join two wires of uniform cross-section.

In the formation of the connecting joint, I preferably make use of a short length of malleable seamless tubing the inside diameter of which is slightly greater than the diameter of the leading-in wires. Into this tube are introduced the leading-in wire and the spud-wire so that they meet midway of the tube. The tubing is now compressed by means of jaws, so that the leading-in wire and the spud-wire are tightly held and the tube has become elliptical in cross-section instead of circular. Also, the tube has been so compressed that it is smaller at the end which grips the spud-wire than it was originally and the excess metal has been caused to flow to the rear end of the tube. The resistor wire is then threaded through the end of the ellipse not occupied by the other wires. Pressure is then applied by means of a die to compress the tube to grip the resistor wire. While this is being done, the tube is still held in the jaws which first compressed it so that the hold of the tube on the leading-in wires and spud-wires will not be broken. The joint thus made has many advantages. It is possible to cut to the exact length necessary the tube, the leading-in wires, and the spud-wires before assembling the same, with the positive assurance that after they have been assembled and the luminants placed in position, the luminants will all occupy the same position with relation to the various parts of the lamp. Furthermore, the percentage of defective joints is very small, due to the fact that the malleability of the tube allows it to be pressed into good contact with the wires. Because of the fact that a seamless tube is used in making the joint, there is no opportunity for

it to open under the influence of the heat generated in the lamp and allow the wires to slip.

I prefer to use a mechanical joint of this character rather than a fused joint, due to the fact that it has all the advantages of a fused joint without the chief disadvantage thereof. The one big advantage of a fused joint is that it can withstand the operating temperature of the lamp. This advantage is also present in the mechanical joint I make use of, because of the use of the seamless tube. A fused joint, however, has the disadvantage that in the making thereof, a certain amount of the wires to be connected together is melted and the wires shortened that much. If my luminant were in the nature of a filament, this feature would not carry much weight, but since the base is generally a tube or a cylinder, it is desirous that it be mounted so that it is horizontal when the lamp is held upright or inverted. To accomplish this, the wires must be of the same length. With a fused joint, allowance would have to be made for the shortening effect, while with the mechanical joint, no such allowance is necessary. Furthermore, a fused joint is not always substantial, due to the fact that the metals may oxidize at the temperature of fusion or the heat conditions may not be right, resulting in a weak joint. My joint, being made cold, is not subject to any such happening. Furthermore, it is practically impossible to know in the case of a defective fused joint, whether the defect was due to the inefficiency of the operator or due to oxidation or heat conditions. With a mechanical joint of this character, the responsibility, in the event of a defective joint, lies with the operator. This is an important feature from a manufacturing point of view, as it is quite easy, under such conditions, to determine the cause of the defective joints and remove it.

Referring now to the drawings:

Fig. 1 is a section taken through one form of my luminant, showing the general arrangement of the connecting joint;

Fig. 2 is a detail showing the first step in making the joint;

Fig. 3 is a like view showing the second step;

Fig. 4 is a perspective of the finished joint;

Fig. 5 is a front elevation of a machine for making this joint;

Fig. 6 is an enlarged detail of this machine;

Figs. 7 and 8 are details on a still larger scale.

The refractory base of the luminant is designated by 1, and the resistor by 2. The ordinary leading-in wires 3, of substantial diameter and good heat conductivity, extend from the stem (not shown). The spud-

wires 4, of lesser diameter and poor heat conductivity, extend from the ends of the leading-in wires and are so shaped as to hold the base. The leading-in wire and the spud-wires are held together by means of a tapered sleeve 5 formed of a short length of seamless tubing. The resistor is also connected with the leading-in wires by means of the sleeve 5.

10 The machine used in making a connecting joint of this character is shown in Figs. 5, 6, 7 and 8. Mounted in the base 10 is the inverted U-shaped member 11 having a hollow column 12 running from the top thereof, the interior of said column being threaded. Engaging in the threads of the column is the screw 13 to which is keyed the wheel 14. Below the wheel 14 on the screw 13 is a nut 13^a which limits the feeding of the 20 screw downwardly. The screw carries a rod 15, the lower end of which comprises the die 16. The connection between the screw and the rod is such that a rotation of the screw causes a reciprocation of the rod, which is prevented from rotating by any 25 suitable means such as a feather. The die 16 has a tapered groove 17 therein.

Attached to the base 10 and extending up into the U-shaped member 11 is a bar 18 30 which is cut out, as at 19 and 20, to form a pair of resilient arms 21. These arms are cut away to form the jaws 22 which together define a slot semi-elliptical in cross-section and which is tapered in the same direction as the die. A headed screw 23 passes through the arms 21 and through 35 one leg of the member 11. Surrounding that portion of the screw 23 which passes through the leg is the sleeve 24. A threaded 40 operating lever 25 is in engagement with the screw 23 and bears against the sleeve 24. A set-screw 26 holds the screw 23 in place. The two screws 27 and 27^a are for the 45 purpose of adjusting and locking one of the arms 21 so that the slot defined by the jaws 22 will be in alinement with the die 16.

In making a joint, the jaws 22 are allowed to open, the sleeve 5 is then placed in the slot defined by the jaws 22, and a leading-in wire is inserted through that end of the sleeve adjacent the larger end of the slot and a spud-wire through the other end so that they meet midway of the sleeve. The lever 25 is now operated in such a way as 55 to pull the jaws 22 together, compressing the sleeve around the wires. Because of the fact that the slot defined by these jaws is tapered, the sleeve will firmly grip both the leading-in wire and the smaller spud-wire. The end of the sleeve gripping the spud-wire will be somewhat smaller than at the start, the excess metal having been forced to flow to the rear end of the sleeve. The sleeve will now be approximately elliptical in cross-section, as shown in Fig. 3,

with one end a trifle larger than the other. The sleeve does not necessarily grip the wires uniformly throughout, as it tapers slightly, but it does grip the wires sufficiently tightly to hold them.

70 The end of the resistor is then threaded through the open space in the sleeve and the die 16 is moved down, bringing the groove 17 in contact with the sleeve 5. The die is caused to move downwardly enough to compress the sleeve around the the resistor. Since the jaws 22 are engaged with the sleeve, there is no chance for the sleeve to distort and destroy the grip on the leading-in and spud-wires. During this operation, 75 still more of the metal is caused to flow toward the large end of the sleeve, as the groove 17 is also tapered. As a result of the tapers in the slot defined by the jaws 22 and in the groove 17, the one end of the 80 sleeve tightly grips the two smaller wires and the rear end grips the large leading-in wire.

85 The joint thus made is highly satisfactory and stands up under any use to which a 90 lamp may be put. It is easy to make and is economical.

I claim as my invention:

1. In an electrical appliance, a leading-in wire of substantial diameter, a supporting wire of lesser diameter, a resistor wire of minute cross-section, and means for joining these wires together with the ends of the leading-in wire and the supporting wire adjacent each other.

95 100 105 110 115 120 125 130

2. In an electrical appliance, a leading-in wire of substantial diameter, a supporting wire of lesser diameter, a resistor wire of minute cross-section, and means for joining the wires together with the ends of the leading-in wire and the supporting wire adjacent each other and the resistor wire in contact with both.

3. In an electrical appliance, a leading-in wire of substantial diameter, a supporting wire of lesser diameter, a resistor wire of minute cross-section, means for joining these wires together with the leading-in wire and the supporting wire in substantial alinement with each other and the resistor wire substantially parallel to both.

110 115 120 125 130

4. In an electrical appliance, a leading-in wire of substantial diameter, a supporting wire of lesser diameter, a resistor wire of minute cross-section and a seamless tube for joining these wires, with the leading-in wire substantially in alinement with the supporting wire and the resistor wire substantially parallel to both.

5. In an electrical appliance, a leading-in wire of substantial diameter, a supporting wire of lesser diameter and a resistor wire of minute cross-section arranged so that the leading-in and supporting wires are substantially in alinement with each other

and the resistor wire substantially parallel to both, and a seamless tube encircling and in holding contact with the said wires.

6. In an electrical appliance, a leading-in wire of substantial diameter, a supporting wire of lesser diameter, and a resistor wire of minute cross-section arranged with the leading-in wire and supporting wire sub-

stantially in alignment and the resistor wire closely associated with both, a substantially 10 comical seamless tube having one end gripping the resistor and supporting wire and the other end gripping the resistor and the leading-in wire.

JOHN ALLEN HEANY.
